UNITED STATES PATENT OFFICE.

LOUIS BERNHARD, OF BOSTON, MASSACHUSETTS.

ARCH CONSTRUCTION.

1,158,776.

Specification of Letters Patent. Patented Nov. 2, 1915.

Application filed February 10, 1915. Serial No. 7,436.

To all whom it may concern:

Be it known that I, LOUIS BERNHARD, of Boston, in the county of Suffolk and State of Massachusetts, have invented a new and 5 useful Arch Construction, of which the following is a specification.

The main object of my invention is to provide an arch for boiler settings, Dutch ovens or other constructions subject to heat which 10 will not crumble and fall to pieces on account of expansion and contraction. This is particularly important in the case of boilers because if the arch, or portions thereof fall, a portion of the exterior of the 15 boiler above the water level will be exposed to intense heat which is likely to result in bursting of the boiler.

My invention consists partly in the combination of a bridge and an arch beneath 20 the bridge with space between the bridge and arch to allow for expansion of the latter.

A feature of my invention consists in an outer and an inner arch, the inner arch being supported by the outer but with provision 25 for relative movement of the inner arch so that it may expand and contract and as supporting means I prefer hangers or binders preferably in the form of double wedges.

Another feature of my invention is the use of magnesia or equivalent material to 30 act not only as a support for building the outer arch, in case the latter is made of a number of elements, such as bricks, but also 35 to act as a heat insulator and as a provider of space for the movement of the lower arch.

A feature of my invention consists in arranging the bricks or other elements of the arch diagonally so as to prevent the application 40 of expansive pressure at right angles to the supporting walls and this feature of my invention, although particularly adapted for locations in which much expansion and contraction of the arch is had is also useful in any arch construction.

Other features of my invention will be pointed out below.

In the drawings: Figure 1 is a rear elevation partly in section of a boiler setting 50 embodying my invention, Fig. 2 is a plan, partly in section, of the setting; and Figs. 3 and 4 are enlarged sectional details.

Walls A A are as usual and lined with fire bricks B B as usual, the clean-out opening 55 below shown at D. Boiler E is provided with fuse plug F, preferably a few inches

below the arch so that normally the water in the boiler will be a few inches above the plug and at the height of the arch.

The inner arch consists of a number of 60 firebricks G and hangers or binders H also of firebrick. Upon this inner arch I spread a layer of magnesia K or other equivalent material and this serves as a frame upon which the outer arch is built, the outer arch 65 consisting of ordinary bricks M and being connected to the inner arch by the binders or hangers H. The ordinary brickwork M' is provided above the outer arch and is supported by it, the brickwork M' and the 70 bricks forming the bridge.

The arch as first built is illustrated in Fig. 3, the hangers H, which are preferably wedge shaped at both ends with straight portions adjacent to the magnesia, being a 75 tight fit in the lower arch but a slightly loose fit in the upper arch.

When the boiler is heated the magnesia contracts, its moisture being driven out, and this leaves a space k so that the inner arch 80 may expand toward the outer arch. At this time the binders being of firebrick will expand slightly possibly to the position shown in dotted lines in Fig. 4.

I preferably provide any suitable raised caps N N to allow for expansion of binders H and to cover and protect them.

When the inner arch contracts it will move away from the outer arch but the magnesia remains in its contracted condition so 90 that space k remains available for the next expansion of the inner arch. During the contraction of the inner arch the binders will contract and be lowered and the lower wedge will spread the inner arch slightly 95 holding it firmly against its abutments. The binders H have a reinforcing and supporting function as to the inner arch and also during the movements of the inner arch a steady function.

In Fig. 2 I illustrate the diagonal arrangement of the bricks or elements of the inner arch this construction providing pressure cornerwise and doing away with direct pressure against the side walls which is a 105 matter of great importance particularly in cases where there are great changes on account of the presence or absence of heat.

It will be observed that I really provide an arch in two parts, the outer part being 110 non-expandable in its nature and also insulated by the magnesia and the inner part be-

ing expandible but without possibility of falling apart or crumbling with the great advantage, among others, of preventing exposure of any portion of the boiler which 5 would result in danger and damage.

I do not claim in this application the method of making arches above described as I intend to make that the subject of a separate application.

10 What I claim is:

1. An arch construction comprising a bridge; an expandible lining therefor separated from the bridge so as to leave a space for the movements of the lining; and means 15 connecting the bridge and lining to support the latter, but permitting relative movement between the bridge and lining, said means moving outwardly when the lining expands but supporting the lining during the ex- 20 pansion.

2. An arch construction comprising an outer arch of ordinary brick; an inner arch of firebrick spaced from the outer arch; and binders at intervals connecting the two 25 arches, but permitting relative movement between them, said binders supporting the inner arch during its expansion and moving outwardly during said expansion.

3. An arch construction for boiler settings 30 and the like comprising an outer arch of ordinary brick; an inner arch of firebrick; a layer of magnesia or the like on said inner arch, said layer being spaced from the outer arch to permit movement of the inner arch; and binders at intervals connecting the two 35 arches but permitting relative movement between them, said binders supporting the inner arch during its expansion and moving outwardly during said expansion.

4. An arch construction comprising an outer arch; an inner expandible arch spaced from the outer arch; and binders connecting the two arches and having sliding connection with the outer arch, each binder being 45 of a double-wedge shape.

5. An arch construction comprising an outer arch; an inner expandible arch spaced

from the outer arch; and binders connecting the two arches but permitting relative movement between them, each binder consisting of 50 an outwardly sloping wedge at one end, an outwardly sloping wedge at the other end and a straight central portion.

6. An arch construction made from elements diagonally disposed so as to prevent 55 the expansion of the arch from applying pressure in a direction perpendicular to the side walls of the structure, the set of elements extending from two diagonally opposite corners being parallel, and the set of 60 elements extending from the other two diagonally opposite corners being at right angles to the first set.

7. An arch construction comprising an outer arch; an inner expandible arch spaced 65 from the outer arch; and binders connecting the two arches and supporting the inner arch during its expansion and having sliding connection with the outer arch, said binders moving outwardly during the ex- 70 pansion of the inner arch.

8. An arch construction comprising an outer arch; an inner expandible arch spaced from the outer arch; and means connecting the two arches but permitting relative movement between them, said means supporting 75 the inner arch during its expansion and moving outwardly during said expansion.

9. An arch construction comprising an inner arch; an outer arch of material less expandible under the action of heat than the material of said inner arch; and intermediate material filling the space between said arches, said intermediate material being contractile under the action of heat. 80

10. An arch construction comprising an inner arch of fire-brick; an outer arch of ordinary brick; and magnesia filling the space between said arches, said magnesia being contractile under the action of heat.

LOUIS BERNHARD.
